BLADE ENGAGEABLE ELECTRIC CONNECTOR

Samuel S. Fortino, New York, N. Y., assignor to
The Gem Electric Manufacturing Company,
Inc., Brooklyn, N. Y., a corporation of New York

Application May 31, 1951, Serial No. 229,225

3 Claims. (Cl. 339—276)

1

This invention relates to a blade engageable electric connector, that is to say, an electric connector which is provided with contacts that are adapted to be coupled with the blades of an electric plug.

By way of example, my invention will be described herein with respect to an electric, multiple, cord connector. However, it is to be understood that this specific form of my invention only is to be considered as illustrative and the invention is not to be deemed as limited thereby except to the extent to which features of such embodiment are pointed out below and specifically are incorporated in the appended claims.

It invariably has been the practice heretofore to provide each contact of a blade engageable cord connector with an attached stiff terminal piece for connection to a cord. Although such connectors are made in huge quantities so that it is desirable to simplify their construction and manufacture in all respects, and although it is recognized that a particularly desirable simplification would be the elimination of the stiff terminal piece, until the present invention such simplification has not been achieved because the very resilience which was needed to enable the contacts to properly function as contacts made it impossible to form a usable terminal in one piece with the contact, and this same resilience prevented such a terminal from acting as a firm support relative to which the contact legs could flex.

It is an object of my invention to provide an improved blade engageable electric connector having one piece terminal-contacts which are not subject to the foregoing drawbacks.

More specifically, it is an object of my invention to provide in a blade engageable electric connector a terminal-contact having in one piece therewith a cord engaging element and a shank that is sufficiently stiff to serve as a base relative to which a contact leg can flex.

It is another object of my invention to provide for a blade engageable electric connector a terminal-contact of extremely simple construction that can be made rapidly and inexpensively by mass production methods.

It is another object of my invention to provide for a blade engageable electric connector a terminal-contact to which a cord can be connected in a simple machine operation.

Other objects of my invention will in part be obvious and in part will be pointed out herein after.

My invention accordingly consists in the features of construction, combinations of elements

2

and arrangements of parts which will be exemplified in the devices hereinafter described and of which the scope of application will be indicated in the appended claims.

5 In the accompanying drawings in which are shown various possible embodiments of my invention,

Fig. 1 is a perspective view of a one piece terminal-contact embodying my invention, the same being illustrated before connection to a cord;

Fig. 2 is a view similar to Fig. 1, but showing the terminal-contact after connection to a cord;

Fig. 3 is an enlarged sectional view taken substantially along the line 3—3 of Fig. 2, and additionally illustrating the operative portion of an upper crimping die which engages the part of the terminal-contact shown in section;

Fig. 4 is an enlarged sectional view taken substantially along the line 4—4 of Fig. 2, and additionally illustrating the operative portion of the upper crimping die which engages the part of the terminal-contact shown in section;

Fig. 5 is a plan view of a multiple cord connector incorporating terminal-contacts embodying my invention, one-half of the body being removed better to show the location of said contacts; and

Fig. 6 is a fragmentary view similar to Fig. 1 showing a modified form of terminal-contact embodying my invention.

30 Referring now in detail to the drawings, and more particularly to Figs. 1 through 5, the reference numeral 10 denotes a terminal-contact constructed in accordance with my invention and consisting of but a single piece of sheet metal.

35 This metal is electrically conductive and is of springy stock in order to impart to the terminal-contact the requisite resilience. In addition, the metal is somewhat ductile. A typical satisfactory metal is red brass, this having a composition of about 85% copper and 15% zinc. Another typical metal with which good results are secured is commercial bronze consisting of about 90% copper and 10% zinc. The sheet stock from which the terminal-contact is made preferably is about 0.02 inch thick.

40 The terminal-contact 10 is blanked from such sheet stock and formed in suitable machinery, well known to the art, to the shape indicated in Fig. 1. At this stage the terminal-contact includes a plurality of wide contact legs 12, 14, 16 whose shape and relative positions are conventional. By way of example, the three contact legs form a T of which the legs 12, 16 are the cross bar and the leg 14 the upright. Each leg is pro-

vided with a dimple 18 near its base and is bowed away from said dimple adjacent the tip of the leg. The foregoing arrangement and construction is conventional.

Pursuant to my invention the terminal-contact further includes a shank 20 which extends away from the cross bar and is located opposite the leg 14. Said shank is broader than the leg 14 and is coplanar with the bases of the three legs. The tip 22 of the shank is angularly offset in the same direction that the legs are bowed, the offset preferably being disposed at substantially a right angle to the plane of the shank. Intermediate the tip of the shank and the point where the shank is joined to the cross bar, the body of the shank is formed with two pairs of upstanding fingers 24, 26, 28, 30.

One pair of fingers 24, 26 is located on one edge of the shank and the other pair of fingers 28, 30 is located on the opposite edge. One finger of each pair, e. g. the inner finger 24, is transversely registered with one finger of the opposite pair, e. g. the inner finger 28, and the remaining two outer fingers 26, 30 likewise are transversely registered. The fingers of each pair are in immediate juxtaposition, that is to say, said fingers are separated by a slit rather than a slot so that the fingers have their adjacent edges in rubbing contact. At the stage that the contact is ready to have a wire connected thereto, this being the condition shown in Fig. 1, the two pairs of fingers extend vertically away from the body of the shank in the same direction as the dimples. Said fingers may be formed simply by striking the same from the shank with suitable tools thereby leaving notches 32, 34.

A standard electric cord 36 of a type adapted to be secured to the terminal-contact 10 constitutes a stranded wire conductor 38 encased in an insulating sheath 40. To secure the cord to the terminal-contact the insulating sheath is stripped off the end of the cord so as to bare the end 42 of the stranded conductor. The cord is laid between the two pairs of fingers with the bare end 42 pointing toward the contact leg 14, and with the end of the sheath between the outer fingers 26, 30 and close to the slits separating the outer fingers from the inner fingers. Thereupon the two pairs of fingers are crimped about the cord. The crimping die includes an upper portion 44 which forces the outer fingers 26, 30 into a semi-circular shape which, in conjunction with the shank, defines a tight loop constrictively embracing the sheath 40. The crimping die further includes another upper portion 46 which forces the inner fingers 24, 28 into engagement with the bare end of the stranded conductor. Said inner fingers are so crimped that their tips 48 are directed downwardly toward the shank whereby said fingers, in conjunction with the shank, roughly define an hourglass, that is to say, a loop whose center is narrower than its ends. Due to this arrangement, the tips of the inner fingers are forced into the bare end of the stranded conductor, separating the strands and making an excellent electrical connection. The outer fingers 26, 30, by tightly gripping the sheath, make an excellent physical connection with the cord thereby serving as a strain relief.

The crimping tool includes a lower half or anvil, not shown, of suitable contour to impart the illustrated shape to the shank.

It should be noted that by selecting a sheet metal stock such as described which is ductile

as well as desilient, I am able to crimp the cord engaging fingers without fracturing the same and can force the fingers into tight engagement with the sheath and stranded conductor without having the fingers back off from the cord after the crimping operation. With the fingers in cord engaging position, said fingers and the cord serve to stiffen the shank of the contact and thus provide a comparatively firm base relative to which the contact legs can be flexed. Moreover because the fingers of each pair are immediately juxtaposed they provide mutual reinforcement for each other, further stiffening the shank and tending to retain the crimped fingers in their cord engaging position.

A pair of terminal-contacts embodying my invention and connected to the ends of a duplex cord are shown in Fig. 5 as they appear when incorporated in a multiple cord connector including a body consisting of two halves 49, only one of which is illustrated, the other being removed so that the terminal-contacts better can be seen. It will be observed that each of the three contact legs when engaged by a blade is arranged to flex relative to the shank 20 and that the offset tip 22 of said shank functions to keep the terminal-contacts spaced apart properly and to prevent the terminal-contacts from rattling.

A terminal-contact 50 embodying a modified form of my invention is shown in Fig. 6. Said contact differs from the terminal-contact 10 in that it is provided with a sharp tine 52 in its shank 54 between two pairs of fingers 56, 58, 60, 62 located on opposite edges of the shank. Said fingers, like the fingers of the terminal-contact 10 are transversely registered.

In the use of the terminal-contact 50 the insulating sheath is not stripped from the stranded electric conductor. The electric cord simply is placed between the two pairs of fingers and the fingers are clinched about the cord in the manner that the fingers 26, 30 are clinched about the cord 36. Desirably the inner fingers 58, 60 first are clinched and then the outer fingers 56, 62. This serves to locate the conductor positively with respect to the terminal-contact, before the fingers 56, 62 are clinched thereby ensuring that the tine 52 will pierce the insulating sheath and become embedded in the stranded wire conductor.

Although my invention has been illustrated in connection with a terminal contact having three legs it will be understood that the invention is not so limited and that any number of legs, one or more, may be used. Likewise it will be appreciated that the immediately juxtaposed transversely registered pairs of fingers, in addition to being used for engaging a cord such as described, may be employed for engaging other conventional electrical elements such for example as the shanks of prong blades.

It thus will be seen that I have provided devices which achieve all the objects of my invention and are well adapted to meet the conditions of practical use.

As various possible embodiments might be made of the above invention, and as various changes might be made in the embodiments above set forth, it is to be understood that all matter herein described, or shown in the accompanying drawings, is to be interpreted as illustrative and not in a limiting sense.

Having thus described my invention, I claim as new and desire to secure by Letters Patent:

1. A terminal-contact for use in a blade en-

gageable connector, said terminal-contact comprising a single piece of ductile resilient sheet metal stock including an entirely flat, flexible, contact leg and a shank, said shank having on one edge thereof a pair of fingers whose adjacent fingers are in rubbing engagement and on the opposite edge thereof another pair of fingers whose adjacent fingers are in rubbing engagement, said pairs of fingers being transversely registered and being adapted to be crimped on an electrical element for engagement therewith, said fingers serving to stiffen the shank whereby to firm the same so as to act as a base relative to which the contact leg can flex.

2. In combination an electric cord constituting a stranded wire conductor and an insulating sheath, the bare tip of said conductor extending beyond the end of the sheath, and a terminal-contact for use in a blade engageable connector, said terminal-contact comprising a single piece of ductile resilient sheet metal stock including an entirely flat, flexible, contact leg and a shank, said shank having on one edge thereof a pair of immediately juxtaposed fingers and on the opposite edge thereof another pair of immediately juxtaposed fingers, said fingers being transversely registered,

5 one pair of fingers being crimped on the bare tip of the conductor and the other pair of fingers being crimped on the sheath adjacent its end, said fingers serving to stiffen the shank whereby to firm the same so as to act as a base resilient to which the contact leg can flex.

10 3. A combination as set forth in claim 2 wherein the fingers which are crimped on the sheath are formed to a semi-circular shape and the fingers which are crimped on the conductor have their ends directed towards the shank and embedded in the conductor.

15 SAMUEL S. FORTINO.
